UNITED STATES PATENT OFFICE.

JOHN G. POTTS, OF DENVER, COLORADO.

RAIN-MAKER.

1,053,133.

Specification of Letters Patent. Patented Feb. 11, 1913.

Application filed October 3, 1911. Serial No. 632,526.

To all whom it may concern:

Be it known that I, JOHN G. POTTS, a citizen of the United States, residing at Denver, in the county of Denver and State of Colorado, have invented new and useful Improvements in Rain-Makers, of which the following is a specification.

This invention relates to devices for producing rain.

20 The object of the invention is to produce a device employing a balloon and a conductor carried thereby and connected with the earth and having means for receiving an electrical charge from the clouds and conveying the same to the conductor.

25 A further object of the invention is the provision of a device of this character employing a balloon carrying a plurality of charge receiving spurs at the top thereof which renders the balloon top heavy so that, should the conductor which carries the charge to the earth become ruptured, the balloon would upset permitting the hot air or gases therein to escape so that it would fall to the ground, and further means for causing the balloon to produce a parachute which renders the fall comparatively easy or, in other words, decreases the momentum thereof.

30 Further objects of the invention will appear as the following specific description is read in connection with the accompanying drawing, which forms a part of this application, and in which:

35 Figure 1 is a side elevation of the device. Fig. 2 is a top plan view thereof. Fig. 3 is a horizontal section on the line 3—3 of Fig. 1.

Referring more particularly to the drawing, 1 represents a balloon which is held in the air in any suitable manner as being inflated with hot air or any suitable means and which is connected to the ground and limited in its forward movement by a metallic conductor 2. This conductor is connected at its upper end by wires which extend together at their central points by a wire or conductor 4 which is adapted to equalize the current stress on the wires and also to provide an attaching means for an intermediate portion of the balloon as hereinafter will be described. The upper end of the wires 3 are connected to a twisted cable 5 which is constructed of a plurality of twisted cables 6, one of which extends vertically from the cable 5 in the form of a receiving spur 7.

The others diverge from the point 8 into receiving spurs 9 which may extend in any suitable direction, here shown the horizontal. Each of these receiving spurs has the separate wires of which it is formed, spread out at the terminal end thereof into a plurality of fingers 10.

60 The balloon is connected at suitable intervals to the conductor 4 by means of clips 11 and is unconnected to the upper portion of the wires 3 above the conductor 4 so that, should the conductor 2 be severed at its connection with the wires 3 by a greater charge than its capacity, the upper portion of the 70 balloon will collapse within the lower portion after the balloon has upset by reason of the weight of the receiving structure at the top of the same and will form a parachute so as to permit the balloon to descend easily 75 under the weight of said receiving structure. The other spurs 12 are projected from the points 13 at the junction of each of the wires 3 with the wires 4 and are constructed in a similar manner to the receiving spurs 6 and 80 9. Immediately below the point of connection of the wires 3 with the conductor 2, a parachute 14 is connected to the conductor 2 so that should the wire conductor 2 be severed from the wires 3 at the point 15, the 85 parachute would spread out and, of course, cause the conductor to drop easily to the ground. In the operation of the device, the balloon is filled with any suitable elevating medium and allowed to ascend until the 90 spurs 6, 9 or 12 come into contact with an electrically surcharged cloud, the cable or conductor tube being played out in any suitable manner and being always connected so as to have a good ground. When the charge 95 in the cloud arcs therefrom to one of the spurs, the atmosphere therearound is consequently expanded and cooled to such an extent that the vapor is condensed and falls in the form of rain. Should the charge be too 100 great for the conductor 2 to carry, the same would be burned off at the juncture thereof and with the wires 3. The balloon being severed from its mooring will ascend until the receiving structure above the same tilts 105 it over, at which time the gas therein will escape and the upper portion of the balloon will collapse into the lower portion and form a parachute, the intermediate portion being, as before stated, connected to the equalizing 110 wire 4. The conductor 2 being severed from the balloon will also fall to the ground and

in order to prevent its too rapid descent, the parachute 14 is applied thereto which, when the cable is released, will spread out as the same drops and reduce the momentum there-
5 of and bring the same gently to earth.

Having thus described the invention, what I claim as new is:-

A device of the class described comprising a balloon, a cable connecting the balloon 10 with the ground, longitudinal cables extending from the connecting cable to the top of the balloon and unconnected therewith, an equalizing cable surrounding the balloon adjacent its center and connected to the last-
15 mentioned cables and directly to the balloon, a weight connected at the top of the

balloon to said last-mentioned cables and adapted to upset the balloon when the same is disconnected from the connecting cable, whereby the portion of the balloon above 20 the equalizing cable will collapse within the portion below the equalizing cable and form a parachute, and a parachute connected to the first-mentioned cable adjacent the balloon. 25

In testimony whereof I affix my signature in presence of two witnesses.

JOHN G. POTTS.
